UNITED STATES PATENT OFFICE.

FRANK B. PEEBLES, OF SYRACUSE, NEW YORK, ASSIGNOR TO THE LAMSON COMPANY, OF SYRACUSE, NEW YORK, A CORPORATION OF MASSACHUSETTS.

POWER CONTROLLER.

Application filed March 26, 1925. Serial No. 18,463.

This invention pertains to power controllers for pneumatic despatch systems and relates more particularly to automatically acting controllers of the so-called minimum flow type of which the patent to Libby No. 968, 578, August 30, 1910, furnishes an early example.

Controllers of this type comprise essentially a valve, hereinafter referred to as the "main valve" located between the transmission tube and an air exhauster or vacuum drum, such valve normally cutting off carrier propelling air flow through the tube when the tube is idle, although there is at 10 all times a continuous flow of air of small volume through the transmission tube, insufficient to propel a carrier and known as the "minimum flow", and a pneumatic, for example a piston or diaphragm, which responds either directly or indirectly to 15 changes in pressure in the tube due to the momentary cutting off or checking of the minimum flow of air incident to the insertion of a carrier in the tube, and which by reason of such response opens wide the main 20 valve to permit carrier propelling air flow through the transmission tube.

In the form of apparatus described in the Libby patent the period during which the 25 valve remains open is determined solely by the operation of a timing device. The present invention is intended to improve the 30 operation of a device of this general type by eliminating the timing device, and in place 35 thereof providing means which responds directly to the change of pressure in the transmission tube incident to discharge of the last 40 carrier therefrom for initiating closure of the main valve.

Systems of the above type are often required to work under very adverse conditions. For example, the exhauster for producing 45 the vacuum may slow down, or by reason of age or lack of attention may be 50 come incapable of maintaining the vacuum for which the system was designed; the transmission tube and other piping, as well as terminal valves and pipe fittings may develop leaks; and the carriers may become so worn as to fit but loosely in the tubes.

The present invention is intended so to improve power controllers of that type which depend solely upon differences in pressure for opening and closing the main

valve as to make them reliable and certain 55 in operation even for extended periods of use when applied to systems in which for one cause or another the vacuum fluctuates irregularly, or is below normal.

In designing my improved controller I 60 have endeavoured to eliminate complicated systems of electrical wiring, keeping such electrical circuits as are employed as short and simple as possible, and also to make the device of compact and rugged construction 65 well able to sustain prolonged wear.

In the accompanying drawings a preferred embodiment is illustrated by way of example:

Fig. 1 being a diagrammatic elevation, 70 partly in section, showing the improved controller installed between one transmission tube of a pneumatic system and the exhaust header thereof;

Fig. 2 is a plan view to larger scale of the 75 improved power controller, the transmission tube being shown in section;

Fig. 3 is a side elevation of the device as viewed from the right side of Fig. 2;

Fig. 4 is a side elevation at right angles 80 to Fig. 3 and partly in section on the line 4-4 of the latter figure, the parts being shown in their normal position with the main valve closed;

Fig. 5 is a view similar to Fig. 4 but showing 85 the main valve open;

Fig. 6 is a fragmentary vertical section substantially on the line 6-6 of Fig. 2 showing the auxiliary controlling devices for determining operation of the main valve;

Fig. 7 is a diagrammatic view illustrating the electrical circuit employed;

Fig. 8 is a view similar to Fig. 6 but showing the corresponding parts in the position which they assume immediately after 95 insertion of a carrier in the transmission tube;

Fig. 9 is a similar view showing the corresponding parts as they are positioned after the main valve has fully opened;

Figs. 10 and 11 are fragmentary vertical sections, to larger scale, illustrating certain of the elements appearing in Fig. 6 but in different operative positions;

Fig. 12 is a side elevation of a sleeve valve 105 constituting an element of the pressure regulating device; and

Fig. 13 is a fragmentary horizontal sec-

tion showing details of a bleeder valve forming a part of the main motor mechanism.

Referring to the drawings and particularly to Fig. 1, the numeral 1 indicates a portion of a central station desk provided with the despatch terminal 2 forming a part of the sending transmission tube 3 leading to an outlying station. The corresponding return transmission tube 4 is provided with the usual normally closed delivery terminal 5 and with the extension tube 6 which passes down through the top of the desk 1 and is connected with the power control apparatus indicated generally by the numeral 7. A suction tube 8 leads from the power control apparatus to the usual suction drum or header 9 in which a vacuum or low pressure is maintained by means of a suitable exhauster, not shown. A continuous air passage or conduit is thus provided extending from the terminal 2 to the exhauster, that portion of the conduit provided by tubes 3 and 4 forming the transmission line.

The improved power control forming the immediate subject matter of the present invention preferably comprises a hollow casing 10 desirably of generally cylindrical form and open at its opposite ends. One end of this casing is closed by a cover 11 secured in position in any desired manner, and the opposite end is closed by a cover 12 of concave form, also removably secured by any suitable means, for example, by the bolts 12^a.

A partition or septum 13 substantially midway the length of the casing 10 divides the latter into an inlet chamber 14 and an outlet chamber 15. The partition 13 is furnished with a valve orifice 16 providing communication between the chambers 14 and 15.

The side wall of the casing 10 is furnished with a flange 17 defining an opening for the reception of the end of the transmission tube extension 6 which opens into the chamber 14. The wall of the chamber 15 is also furnished with an opening defined by a flange 18 adapted to receive the upper end of the suction tube 9, so that the chamber 15 is always in communication with the exhauster. The chamber 14 communicates at all times with the chamber 15 or the pipe 8 by means of a small passage such as may be furnished by a pipe 20 of small diameter or by a small orifice in the partition 13.

The valve orifice 16 is normally closed by means of a valve 21 hereinafter referred to as the "main valve" provided with a stem 22 sliding in a suitable guide opening in a spider 23 projecting from the partition 13 into the chamber 15. The valve 21 is normally held against its seat by means of a compression spring 24 bearing at one end against the cover 11 and at its other against the valve 21.

A flexible diaphragm 26 is clamped at its edges between the end flange 27 of the casing

10 and a marginal flange 28 provided upon the cover 12. This diaphragm thus separates the chamber 15 from a chamber 29 within the cover 12. The diaphragm is connected to the stem 22 by means of clamping plates 30 and a nut 31 engaging the threaded extremity of the stem. Movement of the diaphragm to the left thus retracts the valve 21 from its seat and permits a free flow of air from the transmission tube 6 through the chambers 14 and 15 to the suction tube 8. The chamber 29 communicates with the chamber 15 by means of a restricted passage 29^a preferably controlled by means of a needle valve 29^b.

The upper wall of the chamber 29 is furnished with a valve orifice 32 normally closed by a valve 33 hereinafter referred to as the "auxiliary valve" carried by, or forming a part of, the core of a solenoid 34. This solenoid is secured to the upper surface of the cover 12 by means of bolts 35 and 36, and is furnished with suitable binding posts 35^a and 36^a for the reception of the terminals of an electrical circuit hereinafter described.

Upon the upper part of the casing 10 an auxiliary control mechanism is mounted. This auxiliary control mechanism comprises two meter cylinders 38 and 39 and a regulator cylinder 40 respectively, which may form integral parts of the casing 10 or which may be made separately and mounted upon the latter in any suitable manner. The cylinder 38 is of somewhat larger diameter than either of the others, and preferably somewhat shorter than the others. Each of these cylinders communicates with the external atmosphere at its lower end by means of a suitable passage, for example, by means of the channel 41 extending through the upper wall of the casing 10 and which communicates with the respective cylinders by means of ports 42, 43 and 44, Figs. 6, 8 and 9. The upper part of the cylinder 38 communicates with the outer atmosphere by means of a small bleeder passage 38^a preferably controlled by an adjustable needle valve 38^b.

The cylinders 38 and 39 communicate by means of a port 45 adjacent to the upper end of the cylinder 38, and cylinders 39 and 40 communicate by means of a port 46 adjacent to their upper ends. A small pipe 47 or other suitable conduit connects the upper part of the cylinder 40 with the transmission tube or with the chamber 14 of the casing 10, as may be most convenient.

A piston 48 is arranged to slide within the cylinder 38. This piston is furnished with a stem 49 passing up through the closed top of the cylinder, and this stem is furnished with a fixed abutment 50 forming a support for the lower end of a compression spring 51. A circular washer or annular plate 52 rests upon the upper end of the spring 51, sliding freely on the stem 49. The upper part of the stem 49 passes through a guide

opening in a bridge piece 53, mounted upon supports 54. This bridge piece carries a pair of spaced contact members 55 and 56 respectively, with which the washer or plate 52 is adapted to engage when the piston 48 is raised. The contacts 55 and 56 are connected by means of wires 57 and 58 to the terminals of the solenoid 34, a battery 59 (Fig. 7) or other suitable source of electrical energy being interposed in one of these wires, for example, the wire 57.

A piston 60 is also mounted within the cylinder 39. This piston is longer than the piston 48 and is relatively heavy, so that it tends to return to the lower part of the cylinder when raised. This piston is provided with a stem 61 furnished with a fixed shoulder or abutment 62 upon which a spring 63 rests. An annular plate or washer 64 is supported upon the upper end of this spring. The stem or rod 61 of the piston is guided in an opening in a bridge piece 65 carried by suitable supports 66 and 67 and may, if necessary, be furnished with an auxiliary weight 68 at its upper end. The bridge piece 65 supports a pair of spaced contacts 69 and 70, respectively, with which the plate 64 is adapted to engage when the piston 60 is raised. The contacts 69 and 70 are connected by means of wires 71 and 72 (Fig. 7) to the wires 57 and 58 respectively.

A piston 74 is arranged to slide within the pressure regulator cylinder 40. A spring 75 bearing at its lower end against the piston 74 and at its upper end against the top of the cylinder 40 tends to retain the piston 74 in the lower end of the cylinder. The cylinder 40 is furnished with a cylindrical guide extension 76 projecting from its upper end, and a sleeve valve 77 (Figs. 10, 11 and 12) is arranged to slide within this guide extension. This sleeve valve is closed at its upper end except for a central port or orifice 78, and is normally supported by resting upon the upper end of the stem 73 of the piston 74. This sleeve valve is open at its lower end and has a port 79 in its side wall. This port is of triangular or inverted V-shape, and the sleeve valve is normally so positioned that this port is entirely below the upper end 80 of the guide extension 76 as shown in Fig. 9. When the parts are in this position the port 78 at the end of the sleeve valve is closed by the end of the stem 73.

The operation of the device is substantially as follows, it being understood that when the transmission tube is idle the main valve 21 is closed, the diaphragm 26 occupies the position shown in Fig. 4 and the auxiliary valve 33 is closed. At this time a minimum flow of air is entering the transmission terminal 2 and passing through the pipes 3 and 4 traverses the pipe 20 on its way to the exhauster.

When a carrier is inserted in the transmission tube it obstructs the passage of the minimum flow of air, thus resulting in building up vacuum in the cylinder 38, and causing the piston 48 to rise, thereby closing the circuit through the solenoid 34.

The area of the piston 48 and its weight are so chosen that it tends to rise when subject to the very slightest pressure decrease in the transmission tube, so that even though the tube leak or the carrier be worn, the piston will rise with certainty.

As soon as the circuit through the solenoid 34 is completed the core of the solenoid rises, thus lifting valve 33 and opening the port 32 to the atmosphere. Atmospheric pressure thus acts freely upon the outer side of the diaphragm 26 and as the inner side of the diaphragm is exposed to the pressure in the suction tube 8 the diaphragm moves rapidly to the left, as viewed in Fig. 4, until it assumes the position shown in Fig. 5, thus opening the main valve 21 and permitting a carrier impelling air flow to pass through the transmission tube. When the main valve opens, the vacuum in the transmission tube is increased very considerably, and as this vacuum pressure is transmitted through the pipe 47, the cylinder 40, and the port 46 to the cylinder 39, the piston 60 rises, closing the port 45. The piston 60 is of such weight that it does not rise at all when the carrier is first inserted in the transmission tube and before the main valve opens. When the piston 60 rises and closes the port 45 it also moves the plate 64 into engagement with the contacts 69 and 70, the movement of the piston 60 being such as to compress the spring 63 to a substantial extent.

After the port 45 has closed the piston 48 slowly drops, since air at atmospheric pressure is permitted to bleed in through the port 38^a and thus the circuit through the contacts 55 and 56 is broken, although the circuit through the solenoid is still maintained by the plate 64 engaging the contacts 69 and 70.

The parts remain in this position during the flight of the carrier and so long as a single carrier remains in the transmission tube. If but one carrier be inserted the parts remain as described until this carrier emerges from the tube. When this occurs the pressure in the transmission tube rises slightly and this permits the weighted piston 60 to drop, thus removing the plate 64 from the contacts 69 and 70 and breaking the circuit through the solenoid. The valve 33 now closes and the air is exhausted from the chamber 29 through the passage 29^a. After a very short interval the pressures upon the opposite sides of the diaphragm 26 are so nearly balanced that the spring 24 is able to close the valve 21 thus restoring the parts to initial position.

If, during the flight of the first carrier,

one or more additional carriers are inserted in the tube, the contact plate 64 remains in engagement with the contacts 69 and 70 until the last carrier has been delivered from the tube. As each carrier emerges from the tube there may be a momentary slight increase in pressure in the tube, but since the spring 63 is initially placed under considerable compression such slight fluctuation of the piston 60 as may occur at the delivery of each carrier, other than the last, is insufficient to remove the plate 64 from the contacts 69 and 70, and thus the circuit is maintained until the last carrier is delivered.

As above stated the pistons 48 and 60 are so designed as to be sensitively responsive to a range of pressures such as would be found in a system in which a very poor vacuum was maintained. Since these pistons are so sensitive to pressure fluctuation, it is evident that if installed in a system in which a high vacuum is maintained they would be ineffective for the desired purpose and for this reason the regulator cylinder 40 is provided.

Normally the piston 74 occupies the position shown in Fig. 6 and the sleeve valve 77 rests upon and is supported by the stem 73. Both ports 78 and 79 of the sleeve valve are thus closed. If the vacuum in the system to which the apparatus is applied is greater than that for which the pistons 48 and 60 were designed the piston 74 rises in opposition to the spring 75, thus lifting the sleeve valve 77 until the upper end of the port 79 is exposed above the top 80 of the guide 76. This admits air to the interior of the cylinder 40, thereby decreasing the effective vacuum in the cylinders 38 and 39, although fluctuations in pressure occur in these cylinders corresponding to the fluctuations in pressure in the transmission line, the only difference being that the range of pressures in the cylinders 38 and 39 is lower than that in the transmission tube.

If a very high vacuum is maintained in the transmission tube or if a large number of carriers are simultaneously inserted, which has the effect of increasing the vacuum, the sleeve valve 77 may rise to a considerable extent (Fig. 10) and as the port 79 increases in width from its top toward its bottom, the admission of air to the cylinder 40 increases rapidly, so that the desired pressure in the cylinders 38 and 39 may readily be maintained under all conditions.

If during the operation of the apparatus, the sleeve valve has been lifted, the delivery of the last carrier from the transmission tube with its consequent increase in pressure in the latter tends to permit the piston 74 to return rapidly to its normal position. If the sleeve valve 77 were closed quickly under such circumstances, the net result

might be that the pressure in the cylinder 39, instead of increasing to permit the piston 60 to drop, would actually decrease with the result that the circuit through the solenoid would not be broken. To avoid this action the port 78 is provided and when the piston 74 drops suddenly, upon delivery of the last carrier, the stem 73 of the piston moves away from the port 78 (Fig. 11) and thus permits free entrance of air into the cylinder 40, so that increase in pressure in the cylinder 39 is certain. After the piston 74 has returned to its normal position the sleeve valve 77 gradually returns to its normal position by the action of gravity so that the parts are restored to their initial position.

While I have shown pistons working in cylinders as the auxiliary controlling agents, as well as the pressure regulating means, I contemplate that other forms of pneumatic motor, such for example, as diaphragms disposed in suitable casings may be substituted for the pistons here shown, with such corresponding changes in details as might be necessary in making such substitutions. I also contemplate that the main diaphragm 26 may be replaced by a piston or other form of motor, and that the various parts constituting the controlling apparatus as a whole may be differently arranged and differently proportioned as circumstances may warrant.

It is also to be understood that the pressure regulating means comprising the cylinder 40 or its equivalent may be employed in other environments and in connection with other power control apparatus but that herein specifically illustrated.

I claim:

1. A power controller for use in a pneumatic despatch system having a transmission tube, means for creating a carrier propelling air current in the tube, and a valve for controlling carrier propelling air flow through the tube, said controller comprising a motor for operating the valve and electro-magnetic means for controlling the motor, fixed control means and a contact movable into engagement with the fixed contact means to complete an electrical circuit through the electro-magnetic means, and means for moving the movable contact comprising a pressure responsive element and a coiled compression spring, the spring being substantially collapsed by full movement of the pressure responsive element and thereby maintaining the movable contact in engagement with the fixed contact means regardless of slight subsequent movements of the pressure responsive element.

2. A power controller for use in a pneumatic despatch system of the vacuum type having a transmission tube, an exhauster connected therewith and a valve for control-

ling carrier propelling air flow through the tube, said controller comprising a motor for operating the valve, an electro-magnetic device for determining operation of the motor, 5 a pair of pneumatics of relatively different effective area, each pneumatic having a stem and normally being exposed to transmission tube pressure, a resilient circuit closer movable by each stem, and contact means engageable by the respective circuit closers to close the circuit through the electro-magnetic device.

3. A power controller for use in a pneumatic despatch system of the vacuum type 15 having a transmission tube, an exhauster connected therewith and a valve for controlling carrier propelling air flow through the tube, said controller comprising a motor for operating the valve, an electro-magnetic device 20 for determining operation of the motor, a pair of pneumatics each normally exposed to transmission tube pressure, one of said pneumatics being of greater effective area than the other, each pneumatic having a 25 stem, an annular contact plate encircling each stem, a spring connected to each stem and resiliently supporting the respective contact plates, and contact means engageable by the respective plates for closing the circuit through the electro-magnetic device.

4. A power controller for use in a pneumatic despatch system having a transmission tube, means for creating carrier propelling air flow therein, and a valve for controlling carrier propelling air flow through the tube, said controller comprising a motor for operating said valve, electro-magnetic means controlling the motor valve, a pair of auxiliary pneumatics normally exposed to pressure fluctuations corresponding to those in the transmission tube, one of said auxiliary pneumatics responding to slight change in pressure in the transmission tube due to introduction of a carrier thereby to close the circuit through the electro-magnetic means, the other of said auxiliary pneumatics responding to the relatively greater change in pressure in the transmission tube due to opening of the main valve, said latter auxiliary pneumatic thereby cutting off communication between the transmission tube and the first auxiliary pneumatic.

5. A power controller for use in a pneumatic despatch system of the vacuum type 55 having a transmission tube, an exhauster connected therewith and a valve for controlling carrier propelling air flow through the tube, said controller comprising a motor connected to the main valve for operating the latter, and means for determining operation of the motor comprising an electro-magnetic device, a pneumatic responsive to the slight change in pressure in the transmission tube incident to introduction of a carrier to close the circuit through the electro-magnetic de-

vice, a second pneumatic responsive to the greater change in pressure in the transmission tube due to opening of the valve thereby to cut off communication between the first pneumatic and the tube, said second pneumatic also, by its response to such pressure change, actuating circuit closing means to maintain the circuit through the electro-magnetic device when the first pneumatic becomes inoperative.

6. A power controller for use in a pneumatic despatch system having a transmission tube, means for creating carrier impelling air flow therein, and a valve for controlling carrier propelling air flow through the tube, 80 said controller comprising a motor for operating the valve, and an electro-magnetic device for determining operation of the motor, a pair of independently actuatable circuit closers for closing the circuit through the electro-magnetic device, and a pneumatic for operating each circuit closer, said pneumatics normally being exposed to transmission tube pressure, one of said pneumatics being more sensitive to pressure change than the second, the latter when responding to pressure change cutting off the first pneumatic from the transmission tube.

7. A power controller for use in a pneumatic despatch system having a transmission tube, means for creating carrier impelling air flow in said tube, and a valve for controlling carrier propelling air flow through the tube, said controller comprising a motor for operating the valve, and an electro-magnetic device for determining operation of the motor, a pair of independently actuatable circuit closers for closing the circuit through the electro-magnetic device, a pair of cylinders of different diameters, a piston in each cylinder, the cylinder of smaller diameter constantly communicating with the transmission tube, the larger cylinder normally communicating with the smaller cylinder by means of a port in its side wall and means for transmitting movement from the pistons to the respective circuit closers, the larger piston responding to slight pressure change to actuate one circuit closer to close the circuit through the electro-magnetic device, and the smaller piston responding to a relatively greater pressure change to close the port leading to the larger cylinder and to actuate the other circuit closer to keep the circuit closed through the electro-magnetic device.

8. Pneumatic despatch apparatus having a transmission tube, an exhauster connected therewith and a main valve for controlling carrier propelling flow of air through the tube, a motor for operating the main valve, an electro-magnetic device for determining operation of the motor, a pair of cylinders closed at one end and open to the atmosphere at the other, a piston normally positioned

near the open end of each cylinder, one cylinder constantly communicating with the transmission tube and having a port in its wall leading to the other cylinder; each piston being operative to close a circuit through the electro-magnetic device, the piston in the cylinder which constantly communicates with the transmission tube being slower to respond to pressure change than the other and when it does so respond closing the port leading to the other cylinder.

9. A power controller for use in a pneumatic despatch having a transmission line and a valve for controlling carrier propelling air flow in the line, said controller comprising a pneumatic connected to the valve for operating the latter, pressure responsive means for controlling movement of the pneumatic to open and close the valve, and automatic regulating means for determining the range of pressure to which the pressure responsive means is subjected.

10. A power controller for use in a pneumatic despatch system of the vacuum type having a transmission line and an exhauster connected therewith and a valve for controlling carrier propelling air flow through the line, said controller comprising means responsive to relatively slight differences in pressure in the line to determine opening or closing of the controlling valve, respectively, said means being equally operative without manual adjustment whether a high or low vacuum normally be maintained in the line.

11. A power controller for use in a pneumatic despatch system of the vacuum type having a transmission tube, an exhauster connected therewith, and a valve for controlling carrier propelling air flow through the tube, said controller comprising means for actuating the valve, pressure sensitive means for determining the operation of the valve actuating means, said pressure sensitive means being operative at a predetermined pressure range slightly below atmospheric pressure, and means for transmitting pressure from the transmission tube to said pressure sensitive means and means for changing said transmission tube pressure, if of a higher order of vacuum, to bring it within said predetermined pressure range.

12. A power controller for use in a pneumatic despatch system of the vacuum type having a transmission tube in which a relatively high range of vacuum pressure normally obtains, an exhauster connected to the tube, and a valve for controlling carrier propelling air flow through the tube, said controller comprising means for actuating the valve, pressure sensitive means for determining operation of the valve actuating means, said pressure sensitive means being operative at a lower range of vacuum pressures than obtains in the transmission tube,

and means for transmitting transmission tube pressure to said pressure sensitive means and for changing such transmitted pressures to bring them within the range of operation of said pressure sensitive means. 70

13. A power controller for use in a pneumatic despatch system having a transmission tube, means for creating carrier impelling air flow in the tube, and a valve for controlling carrier propelling air flow through the tube, said controller comprising a pressure actuated element sensitively responsive to pressure fluctuations within a normal range varying little from atmospheric pressure, means for transmitting transmission tube 80 pressure to said pressure actuated element, and means for changing such transmitted pressure, if different from the normal range for which the pressure actuated element is designed, to bring it within such range. 85

14. A power controller for use in a pneumatic despatch system of the vacuum type having a transmission tube, an exhauster connected therewith and a valve for controlling carrier propelling air flow through the tube, said controller comprising a casing having a chamber therein, said chamber communicating with the transmission tube, a pressure actuated element forming one wall of said chamber, said element being sensitively responsive to a lower range of vacuum pressures than that of the transmission tube, and means for admitting atmospheric air to said chamber whereby to reduce the vacuum therein and bring it within the range of pressures to which said element is responsive. 95

15. A power controller for use in a pneumatic despatch system having a transmission tube, means for creating carrier impelling air flow in the tube, and a valve for controlling carrier propelling air flow through the tube, said controller comprising a pneumatic connected to the valve for operating the latter, a casing having a chamber therein communicating with the transmission tube, a pressure actuated element forming one wall of said chamber, means actuatable by said element for determining operation of the pneumatic, said element being responsive to a range of pressures nearer to atmospheric pressure than obtains in the transmission tube, and a pressure actuated device for opening said chamber to the atmosphere whereby automatically to maintain the pressure therein within the range at which said pressure sensitive element is operative. 110 115

16. A power controller for use in a pneumatic despatch system of the vacuum type having a transmission tube, an exhauster connected therewith, and a valve for controlling carrier propelling air flow through the tube, said controller comprising a pneumatic connected to the valve for operating the latter, an auxiliary valve for determining 125 130

actuation of the pneumatic, a casing having a chamber therein communicating with the transmission tube, an element responsive to pressure fluctuation in said chamber to operate the auxiliary valve, and means responsive to vacuum in excess of a predetermined amount in the transmission tube to admit atmospheric air to said chamber.

17. A power controller for use in a pneumatic despatch system of the vacuum type having a transmission tube, an exhauster connected therewith, and a valve for controlling carrier propelling air flow through the tube, said controller comprising a pneumatic connected to the valve for operating the latter, said pneumatic being exposed on one side to exhauster pressure and normally closed from the atmosphere at its other side, a normally closed auxiliary valve for admitting atmospheric pressure to act upon the latter side of the pneumatic, means for operating the auxiliary valve comprising an auxiliary pneumatic forming a movable wall for a chamber communicating with the transmission tube, and a pressure actuated valve operable to admit atmospheric pressure to said chamber in direct ratio to the increase in vacuum in the transmission tube above a predetermined point.

18. A power controller for use in a pneumatic despatch system having a transmission tube, means for creating carrier impelling air flow in said tube, and a valve for controlling carrier propelling air flow through the tube, said controller comprising a pneumatic connected to the valve for operating the latter, said pneumatic being exposed on one side to transmission tube pressure and normally closed from the atmosphere at its other side, a normally closed auxiliary valve for admitting atmospheric pressure to act upon the latter side of the pneumatic, means for operating the auxiliary valve comprising an auxiliary pneumatic forming a movable wall for a chamber communicating with the transmission tube, a normally closed valve for admitting atmospheric air to said chamber, and a pneumatic exposed to transmission tube pressure for opening said valve.

19. A power controller for use in a pneumatic despatch system of the vacuum type having a transmission tube, an exhauster connected therewith and a valve for controlling carrier propelling air flow through the tube, said controller comprising a pneumatic connected to the valve for operating the latter, said pneumatic being exposed on one side to exhauster pressure and normally closed from the atmosphere at its other side, a normally closed auxiliary valve for admitting atmospheric pressure to act upon the latter side of the pneumatic, means for operating the auxiliary valve comprising an auxiliary pneumatic forming a movable wall for a chamber communicating with the

transmission tube, a reciprocable sleeve valve having a V-shaped port for admitting air to said chamber, said valve normally being closed, and a pneumatic for opening said sleeve valve.

20. A power controller for use in a pneumatic despatch system of the vacuum type having a transmission tube, an exhauster connected therewith and a valve for controlling carrier propelling air flow through the tube, said controller comprising a main pneumatic connected to the valve for operating the latter, means for determining operation of the main pneumatic comprising an auxiliary pneumatic forming a movable wall for a chamber communicating with the transmission tube, and means for admitting atmospheric air to said chamber comprising a cylindrical guide, a sleeve valve sliding in the guide, said valve having a port of inverted V-shape in its wall, said port normally being disposed within and below the end of the guide, and means for moving the sleeve to expose the port beyond the end of the guide.

21. A power controller for use in a pneumatic despatch system of the vacuum type having a transmission tube, an exhauster connected therewith and a valve for controlling carrier propelling air flow through the tube, said latter controller comprising a main pneumatic connected to the valve for operating the latter, a casing having communicating chambers, one at least of said chambers communicating with the transmission tube, means responsive to pressure fluctuation in one of said chambers for determining operation of the main pneumatic, an auxiliary pneumatic in another chamber, said auxiliary pneumatic having a stem, and a valve actuatable by said stem for admitting atmospheric air to said latter chamber.

22. A power controller for use in a pneumatic despatch system having a transmission tube, means for creating carrier impelling air flow therein, and a valve for controlling carrier propelling air flow through the tube, said controller comprising a main pneumatic connected to the valve for operating the latter, a casing having communicating chambers, one at least of said chambers communicating with the transmission tube, means responsive to pressure fluctuation in one of said chambers for determining operation of the main pneumatic, an auxiliary pneumatic in another chamber, said auxiliary pneumatic having a stem, and a valve actuatable by said stem for admitting atmospheric air to said latter chamber.

23. A power controller for use in a pneumatic despatch system of the vacuum type having a transmission tube, an exhauster connected therewith and a valve for controlling carrier propelling air flow through the tube, said controller comprising a main

- pneumatic connected to the valve for operating the latter, a casing having communicating chambers, one at least of said chambers communicating with the transmission tube, means responsive to pressure fluctuation in one of said chambers for determining operation of the main pneumatic, an auxiliary pneumatic in another chamber, said auxiliary pneumatic having a stem, a cylindrical 10 guide extending upwardly from the latter chamber, and a sleeve valve sliding in said guide, said valve having a port in its upper end, the end of the stem of the auxiliary pneumatic normally closing said port.
- 15 24. A power controller for use in a pneumatic despatch system of the vacuum type having a transmission tube, an exhauster connected therewith and a valve for controlling carrier propelling air flow through the 20 tube, said controller comprising a main pneumatic connected to the valve for operating the latter, a casing having communicating chambers, one at least of said chambers communicating with the transmission tube, 25 means responsive to pressure fluctuation in one of said chambers for controlling operation of the main pneumatic, an auxiliary pneumatic in another chamber, said auxiliary pneumatic having a stem, a cylindrical 30 sleeve valve normally supported by said stem, said valve having a port in its end normally closed by the end of the stem, and a spring for restoring the auxiliary pneumatic to normal position after being lifted by differential pressures at its opposite sides. 35
25. A power controller for use in a pneumatic despatch system of the vacuum type having a transmission tube, an exhauster connected therewith and a valve for controlling carrier propelling air flow through the 40 tube, said controller comprising a main pneumatic connected to the valve for operating the latter, a casing having communicating chambers, one at least of said chambers communicating with the transmission tube, 45 means responsive to pressure fluctuation in one of said chambers for determining operation of the main pneumatic, an auxiliary pneumatic in another chamber, said auxiliary pneumatic having a stem, a cylindrical 50 guide projecting from the latter chamber, a sleeve valve sliding in said guide, said valve having a port in its side wall normally disposed below the end of the guide and having a second port in its end, the latter port 55 normally being closed by the end of the stem, and a spring for restoring the auxiliary pneumatic to normal position after being moved by differential pressures upon its opposite sides, the sleeve valve being restored to normal position by the action of 60 gravity.

Signed by me at Syracuse, N. Y., this twenty-third day of March, 1925.

FRANK B. PEEBLES.
